No. 35,490.

PATENTED JUNE 3, 1862.

J. B. SCHALKENBACH.
PIANO ORCHESTRA.

UNITED STATES PATENT OFFICE.

JNO. BAPTIST SCHALKENBACH, OF TRIERS, PRUSSIA, ASSIGNOR TO E. JUSTH, OF SAN FRANCISCO, CALIFORNIA.

PIANO-ORCHESTRA.

Specification of Letters Patent No. 35,490, dated June 3, 1862.

To all whom it may concern:

Be it known that I, JOHN BAPTIST SCHALKENBACH, of the city of Triers, in the Kingdom of Prussia, have invented a new and 5 Improved Musical Instrument, which I denominate the "Piano-Orchestra;" and I do hereby declare that the following is a full, clear, and exact description of the same, reference being had to the accompanying 10 drawings, forming part of this specification, in which—

Figure 1, is a front elevation of the instrument. Fig. 2, is a side elevation of the same. Fig. 3, is a transverse section of the 15 key board and principal chest of the wind portion of the instrument. Fig. 4, is a plan of the interior of the chest with its covers removed.

Similar letters of reference indicate corresponding parts in the several figures.

This invention consists in the application of musical instruments played by percussion such as the large and small drums, cymbals, tam tam, triangle, &c., to harmoniums, piano 20 fortes, organs or other instruments played by keys in such manner as to allow the performer to bring the said instruments into play by making use of his hand or forearm during the execution of a piece of music 25 without causing an interruption of the harmonies and passages.

It also consists in novel mechanism for playing upon the small or rolling drum in order that when so applied and played by 30 keys it may realize nearly all the effects executed by a skilful drummer with his drum sticks.

It also consists in a mechanism applicable to harmoniums, organs, and other wind instruments played in a similar manner by 35 means of which the keys may be stopped with their valves in an open condition in order to permit the player to act freely on the percussion instruments during the sustained accords or tunes whenever it is desired to produce a particular effect with the latter instruments.

It also consists in a set of metallic funnels or trumpets adapted to the acoustical holes

or harmoniums &c. through which the 50 sound by applying the tremolo-valve receives the character of a trumpet (tuba).

It also consists in uniting the said percussion instruments in one, which being played upon by a single artist in the same manner 55 as any other instrument played by keys may be employed in an orchestra or for accompaniment in general.

A, is the chest of the harmonium supported by a pillar B, erected upon a base C. 60 On each side of the pillar there is arranged one of two bellows D, D, to be worked by the feet; and the pillar serves as a wind passage between the bellows and the chest A.

E is the key board of the harmonium. 65

On the top of the harmonium is a harmoniflute F, the wind chest of which is in communication with that of the harmonium.

G is the keyboard of the harmoniflute.

Above the harmoniflute is a carillon or 70 chime instrument N, composed of a set of bells.

H is the keyboard of the carillon. The hammers for striking the bells of the carillon are behind them and not exposed to 75 view in Fig. 1. b, b, are there dampers.

From the bottom of the chest of the harmonium the small or rolling drum I, is suspended by cords or wire links c, c. The cymbal J, is suspended by a cord d, and the triangle P, is suspended by one or more cords. The drum I, being near the right 80 hand end of the harmonium and the cymbal and triangle near the other end.

At the back of the harmonium between 85 the chest A, and the base B, the large drum K, is secured by cords or wires f, f, above and below, the head of the drum being vertical and toward the front of the instrument.

g, g, are the drum sticks for playing the small or rolling drum I, composed of flattened steel springs having each a hollow copper knob g³, at one end to constitute the heads for striking the drum and attached at its other end to one of two butts h, h, which are pivoted by a pivot i, to a light but rigid metal hanger L secured to 90 95

the front of the chest A, near the right hand end thereof. The said butts have applied to press upon them, in front and below the pivot i , springs j , j , made of pieces 5 of watch spring for the purpose of holding up the sticks out of contact with and some distance above the drum when it is not being played upon; and the said butts have also hinged or pivoted to them behind the 10 pivot i , metal rods g' , g' , working through suitable guides and furnished at their upper ends with knobs g^2 , g^2 , of ivory or other suitable material to enable them to be used as keys by the fingers, hand, wrist, or fore 15 arm of the player for the purpose of playing the drum I. By pressing down the knobs g^2 , g^2 , the balls g^3 , g^3 , are caused to strike the drum I, the movement of the springs g , g , and j , j , in connection with the elasticity of the 20 surface of the drum, produces by a single depression of the keys C, C, a rolling which can be freely lengthened or stopped, maintained in pianissimo or heightened to fortissimo rollers, dry blows or the latter intermixed with the rollers, every rhythm and shade of tune executable by an able drummer are easily executed by means of this mechanism, of the keys are played upon 25 with two fingers. The degree of the depression of the knobs g^2 , g^2 , is not limited by a stop but the balls, or respectively the sticks g , g , may be pressed down further than to the level of the surface of the drum, and it is by this means that the performer 30 is enabled to execute blows of any strength and the rolling of the drum. By adding a third stick made rigid but otherwise operated by a similar knobbed rod or key the variety of the character of the blows on 35 the drum I, might be further increased.

The drum stick M, for playing the large drum K, is made with a padded head M^2 , like the sticks for playing such drums by hand. The said stick is attached to a rock-shaft k arranged in suitable bearings under 40 and near the back of the instrument; and an arm k , of this rock-shaft is connected by a rod k^2 , with an elbow lever l^4 , working on a fulcrum pin in a hanger N, arranged by 45 the side of L, and this elbow lever has connected with it an upright ivory knobbed rod m , which is arranged close to the knobbed rods g' , g' , to be played upon by the right hand when the player desires to 50 strike the large drum. The said rod m , has applied to it a spring m' , which serves to raise it when relieved of the pressure of the hand or fingers, and to draw back the drum-stick M, from the drum. The pressure 55 given by the hand of the player to the rod m , to play the large drum should have the character of an elastic throw.

The cymbal J, is played by means of sticks or hammers n , o , p , applied in a

hanger Q, secured to the front of the chest A, near the left hand end thereof, the mode of applying the said sticks or hammers in said hanger corresponding with that in which the drum sticks g , g , are applied in the hanger L. n' , o' , p' , are the rods with 65 knobs n^2 , o^2 , p^2 , serving as keys to play upon the cymbal with the fingers hand or wrist. The hammer n , has its head composed of a metal ball and therefore produces a purely metallic sound; but the head of o , is covered with leather and felt and thus produces the dull bell-like sound proper to the tam-tam; and p , is arranged to strike near the center of the cymbal to produce the silvery tone of small cymbals. 75

The triangle is played by a stick q , of iron or steel applied in the hanger Q, in the same manner as the hammers n , o , p , but having instead of a knob on the rod q' , by which it is played, a long straight head q^2 , 85 to enable it to be played by the wrist of the left hand whatever the position of that hand may be in playing upon the harmonium. The rod q' , may have attached to it a movable piece by which it may be made 90 to produce the operation of the key n^2 , and hammer n , by the act of playing the triangle.

The percussion instruments, viz: the drums, cymbal and triangle applied and 95 furnished with playing mechanism as above described can be easily managed during the playing of the harmonium by the wrist or the fore-arm; but when it is desired to produce higher effects with small drum I, two 100 of the fingers of the player must be employed, and in such case the right or left hand has to leave the key board E, while the other one continues the harmony or performs appropriate passages on the harmonium. In order however to facilitate the 105 playing and realize the fullness of the accords and also to allow the percussion instruments to play their part during the final resounding of the accords; and finally to 110 produce very great effects on harmoniums and organs generally, there is an especial mechanism peculiar to this instrument which I will proceed to describe with reference to Figs. 3 and 4.

E, E, are the keys and T, T, their attached valves. The keys have springs r , r , applied to them near their rear ends for the purpose of depressing the said ends and closing the valves when the front ends of the 115 keys are not subject to the pressure of the fingers in playing.

In the back part of the chest A, behind the keys, two light rockshafts s , s' , of iron or steel are arranged in line with each other parallel with the front and back of the chest, 120 said rockshafts being supported in suitable bearings or between suitable centers to per-

mit of their free oscillation. The two rockshafts extend the whole length of the key board, each extending half or any suitable portion of the length. They are of half 5 round form in their transverse section and each one has applied to it at the end which is next the end of the chest, a spiral spring t , which tends to turn it to a position in which its flat side is upright and in front as shown 10 in Fig. 3 in black outline. Each one has connected with it a cord u , by a pull of which it may be turned in opposition to the action of the spring for the purpose of presenting the flat side upward as shown in red 15 outline in Fig. 3, and the two cords u , u , pass over pulleys u' , u' , arranged in openings on the back of the chest and thence down to links u^2 , u^2 , which connect them with two small elbow levers u^3 , u^3 , which work close to 20 the outside of the back of the chest or fixed fulcra secured in the chest, and which are connected each with the near end of one of two horizontal levers S , S' , arranged below the chest in such a manner that their front 25 ends project forward from under the chest at a short distance apart to serve as handles by which to work the said levers S , S' , to bring the rockshafts to the position shown in Fig. 3, in red outline the necessary movement of the said levers being effected by the player pressing the said handles toward 30 each other either with his hands or knees, or the movement of one of the levers being effected to turn only its respective rockshaft 35 s , or s' , by pressing that lever alone toward the other one. The result obtained by thus turning either of the rockshafts to the position shown in red outline in Fig. 3, is to cause such of the keys E , E , in front of the 40 said rockshaft as may have been depressed to open their respective valves, previous to its being turned to be retained in that condition to continue the tones as long as may be desired after the player has removed his 45 fingers from them and while he may be playing on the percussion instruments. The connection provided between the keys and the rockshafts s , s' , for this purpose consist of elastic hooks w , w , secured to the near 50 ends of the keys. These hooks are so formed and applied that any of them whose keys have not been depressed at the front ends for the purpose of raising their near ends and opening the valves which their respective rockshafts s , or s' , is in the position represented in black in Fig. 3, will press against the flat side of the rockshaft as shown in black outline in Fig. 2 and will have their points below the lower edge of the said flat 55 side so that by the turning of the rockshaft to the position indicated in red outline in the same figure, the said hooks will not be caught by the rockshaft and so caused to have the near ends of their keys raised to 60

open their respective valves but that when the front ends of their keys are depressed to open the valves while their respective rockshaft is in the aforesaid position the points of the said hooks will be brought to such a height that by turning the rockshaft 70 to the position shown in red the flat side of the latter will be brought under the said points and so caused to retain the keys in that position after the pressure on their front end has been removed and has returned to the position shown in black. 75

The hooks w , w , do not interfere with the ordinary action of any of the keys but those which have had their front ends depressed before the rock shaft was turned 80 from the position shown in red to that shown in black, as the hooks press easily and slide freely up and down against the surface of the rockshaft when the key is operated in playing, while the rockshaft is 85 in either position.

U , U , are metallic trumpet tubes or funnels fitted to the air holes of the chest A , to give the sound of the harmonium very full trumpet like tones. These tubes or funnels are 90 fitted with dampers U' , U' . Any number of such tubes or funnels may be employed.

V , W , X Y are wooden pipes connected with the chest of the harmonium and having their valves operated by keys V' , W' , 95 X' , Y' , for imitating the cry of the cuckoo.

Z is what is commonly termed a steam whistle placed upon the chest of the harmonium and having air admitted through it by the opening of a valve by means of a 100 key Z' .

The drums cymbals and triangles arranged and played by mechanism in a manner similar to what has been herein described may be employed as a separate instrument. 105

What I claim as my invention and desire to secure by Letters Patent is—

1. The application in combination with harmoniums piano fortés or other instruments played by keys, of percussion instruments such as drums cymbals tam-tam and triangle arranged substantially as herein described whereby the player is enabled to play the said percussion instruments by 110 making use of his hand or arm while playing with the fingers on the keys of the other instrument substantially as herein set forth.

2. The use for playing the drum or cymbal of elastic sticks g , g , n , o , p , arranged 115 and having springs j , j , applied to their butts and operated by means of keys g^2 , g^2 , n^2 , o^2 , p^2 , connected with the butts all substantially as herein set forth.

3. The employment of mechanism substantially such as is represented in Figs. 3 and 4, and herein described, applied to operate upon the keys to retain the valves of the 125

harmonium or other wind instrument on an open condition when desired substantially as herein set forth.

4. The metallic tubes or funnels U, U, applied in combination with the harmonium or other reed instrument substantially as herein specified.

5. The relative arrangement of the several percussion instruments consisting of the 10 drum cymbal tam-tam and triangle and

their playing mechanism substantially as herein set forth.

In testimony whereof I have hereunto set my signature this 18th day of March, 1862, valuable for the specification of any patent 15 for piano-orchestra.

J. BAPT. SCHALKENBACH.
